US0D1012070S

(12) **United States Design Patent** (10) Patent No.: **US D1,012,070 S**
(45) Date of Patent: ** Jan. 23, 2024

(54) **ANTENNA APPARATUS**

(71) Applicant: **Space Exploration Technologies Corp.**, Hawthorne, CA (US)
(72) Inventors: **David Milroy**, Kirkland, WA (US); **Duncan Edwin Adams**, Redmond, WA (US); **Anthony Sims**, Manhattan Beach, CA (US); **J. Gabriel Rustia**, Los Angeles, CA (US)
(73) Assignee: **Space Exploration Technologies Corp.**, Hawthorne, CA (US)
(**) Term: **15 Years**
(21) Appl. No.: **29/861,219**
(22) Filed: **Nov. 28, 2022**

CLAIM

The ornamental design for an antenna apparatus, as shown and described.

DESCRIPTION

FIG. 1 is a bottom perspective view of an antenna apparatus showing our new design in a first configuration;

FIG. 2 is a left side view of the antenna apparatus shown in FIG. 1;

FIG. 3 is a top perspective view of the antenna apparatus of FIG. 1 shown in a second configuration;

FIG. 4 is a bottom perspective view of the antenna apparatus of FIG. 3;

FIG. 5 is a right side view of the antenna apparatus shown in FIG. 3;

FIG. 6 is a left side view of the antenna apparatus shown in FIG. 3;

FIG. 7 is a top view of the antenna apparatus shown in FIG. 3;

FIG. 8 is a bottom view of the antenna apparatus shown in FIG. 3;

FIG. 9 is a front view of the antenna apparatus shown in FIG. 3; and,

FIG. 10 is a rear view of the antenna apparatus shown in FIG. 3.

The broken lines shown in the Figures show portions of the antenna apparatus, that form no part of the claimed design. The broken lines immediately adjacent the shaded areas represent the bounds of the claimed.

The shade lines in the Figures show contour and do not claim surface ornamentation or treatment.
